DEVICE FOR SURVEYING WELL BORES

Emmett M. Irwin and Bruce H. Rule, Pasadena,
and George E. Lewis, Alhambra, Calif., assign-
ors to Cooperative Development Co., Los An-
geles, Calif., a corporation of California

Continuation of application Serial No. 253,124,
January 27, 1939. This application April 29,
1941, Serial No. 390,938

10 Claims. (Cl. 33—205.5)

Our invention relates to oil well survey de-
vices and has particular reference to an instru-
ment which may be employed for the purpose of
measuring the course of a well bore by determin-
ing the deviation thereof from the true vertical
and the direction which such deviation takes.

This application is a continuation of our pre-
viously filed application Serial No. 253,124, filed
January 27, 1939, and entitled "Device for sur-
veying well bores."

In oil well practice, the well bore is drilled
from the ground surface, either in a true vertical
direction from the ground surface toward an
oil pool located vertically below the starting
point of the well, or along a predetermined or
prescribed course directed toward an oil pool
which may be offset in a known direction from
the point on the ground surface at which the well
bore is started. In either event it is desired that
the driller know from time to time whether or
not the well bore is following the true prescribed
course and for this purpose it is the present
practice to employ survey instruments which
may be lowered into and passed through the well
bore to make measurements of the direction in
which the well bore is traveling; that is, whether
or not the well bore has deviated from a true
vertical line and the compass direction in which
such deviation occurs as well as the extent or
angle of such deviation.

Heretofore all of the survey instruments which
have been found practicable for this use have in-
cluded devices which are adapted to be lowered
into a well bore upon a wire or cable and stopped
therein at a desired point in the bore, the in-
strument then being permitted to make the
measurements, after which the instrument is
withdrawn to the ground surface and there opened
in order to permit the record of the measure-
ment made to be translated and read. One of
the primary difficulties encountered in the pre-
vious devices is that during the survey of a well,
either in making a single angle of deviation mea-
surement and direction of deviation mea-
surement at some one predetermined point in the
well or in making a survey of the complete well
by making a series of records at different depths
along the course of the bore, it is impossible
for the person making the survey to determine
whether or not an actual measurement and re-
cording of the measurement has been made by
the instrument so that after the instrument has
been withdrawn to the ground surface it is fre-
quently found that no record has been made
at one or more points along the survey.

Another deficiency of the previous devices is
that operating mechanisms for causing them to
make their records usually consist of electric
circuits and requires the location upon the in-
strument of suitable sources of electric current
such as dry batteries, so that it is impossible to
determine, until the device has been withdrawn
to the ground surface, whether such sources of
current have been depleted or destroyed to ren-
der the instrument inoperative at the very time
it is desired that it should make its measure-
ments.

It is an object of our invention, therefore,
to provide a survey instrument which may be
lowered to any desired depth in a well bore upon
a cable which constitutes an electric conductor
over which electric power at predetermined volt-
age may be transmitted down through the cable
to the instrument to supply operating current
therefor and in which the measurements made by
the instrument may be transmitted to the ground
surface through the same electrical conductor.

Another object of our invention is to provide
an instrument of the character set forth wherein
in the measurements taken by the instrument
at any point along the course of the well bore
may be instantly transmitted to the ground
surface and there received and translated or re-
corded so that the person making the survey
is constantly advised as to whether or not the
instrument is in operative condition and is actu-
ally making recordings or measurements at the
desired points.

Another object of our invention is to provide
an instrument of the character described wherein
in the instrument may be lowered into a well
bore without regard to the compass orientation
of the instrument itself but in which the in-
strument is provided with means for determin-
ing its varying orientation relative to the ori-
entation of the drift of the well bore, and a means
for determining the varying orientation of the
instrument relative to a true north direction,
both of which determinations will be transmitted
to the ground surface to permit direct reception,
translation and recording thereof at the ground
surface, permitting direct reading at the ground
surface of the effective orientation of the drift
of the well bore.

Another object of our invention is to provide
a device as set forth in the preceding paragraphs
wherein novel means is employed to determine
the orientations of the drift of the bore and the
position of the instrument relative to the true

north, which means requires a minimum of mechanical power for its operation.

Another object of our invention is to provide a measurement of the character set forth wherein in a plurality of angle inclination measuring devices are employed, each of which is responsive to the tilting of the instrument a different predetermined amount away from the vertical and in which an electric circuit is completed by each of the angle measuring devices to produce an indication at the ground surface of the number of such devices that have been so positioned as to complete their respective circuits.

Another object of our invention is to provide an instrument of the character set forth and a system for receiving the indications or measurements at the ground surface wherein visual readings of the measurements may be instantly made.

Other objects and advantages of our invention will be apparent from a study of the following specification, read in connection with the accompanying drawings, wherein:

Fig. 1 is a diagrammatic view of a well bore and the manner in which our instrument may be employed for surveying the course of the bore;

Fig. 2 is a vertical sectional view taken through an instrument constructed in accordance with our invention and illustrating the various angle measuring devices, sequence switching apparatus, borehole orientation analyzing device and compass point orientation analyzing device, and the required electrical apparatus such as rectifiers and resistors which are required for the making of the measurements and the translation of the intelligence to the ground surface;

Fig. 3 is a diagrammatic perspective view of a portion of the apparatus contained in the instrument shown in Fig. 2 including the sequence switching device, the motor or motive means required for operating the same, the bore hole orientation analyzing device and the compass point orientation analyzing device, and illustrating the mechanical connections therebetween;

Fig. 4 is a schematic wiring diagram illustrating the electrical connection required between the apparatus at the ground surface and the connections for the apparatus of the instrument itself;

Fig. 5 is a detailed perspective view of one form of recording device which may be employed at the ground surface for the reception and translation of the indications produced by the instrument in the well; and

Fig. 6 is a view of section of record chart which will be produced by our instrument and with our equipment.

Referring to the drawings, illustrated in Fig. 1 is a typical oil well which may be either a completed oil well or an oil well bore in the process of drilling. The bore is illustrated at 1 as extending from the ground surface 2 in a substantially true vertical line to the point 3 at which the course of the well bore deviates from the vertical and continues along the non-vertical path to the lowest point or bottom of the hole indicated at 4. For purposes of illustration only we have shown a derrick structure 5 disposed above the upper end of the well bore and through which the drilling tools and other apparatus required therefor may be handled.

Assuming that it is desired to survey the course of the well bore 1 and to determine the angle to which the hole has deviated from the true vertical as well as the compass direction in which deviation occurs, we employ our survey instrument indicated generally at 6 mounted at one end of an

electric conductor cable 7 which may be and preferably is disposed upon a suitable drum (not shown) carried in a service truck indicated at 8; which service truck may also include as a part of its equipment the necessary electric current generating apparatus and the recording apparatus for receiving and translating the indications or measurements produced by our instrument. For purposes of convenience in lowering the instrument into and raising the instrument out of the well, we provide a pulley structure 9 which may be suspended in any suitable manner within the derrick 5 and over which the cable 7 may extend.

By referring particularly to Fig. 2 it will be observed that our instrument includes a suitable case or housing 10 which may be constructed as an elongated tubular housing preferably open at both ends, the lower end 11 thereof being closed by a suitable nose piece 12 preferably rounded in order to permit the same to pass readily about any obstructions which may be contained within the hole. While it will be understood by those skilled in this art that our instrument may be lowered into the open hole, it is preferable to lower the instrument into and through a casing or other pipe contained within the hole. For purposes of illustration herein we have, however, shown the instrument being lowered into the open hole in which event the instrument will be considerably smaller in diameter than the diameter of the well bore, and in order to maintain the longitudinal axis of our instrument and its casing accurately aligned with the longitudinal axis of the well bore, we provide a plurality of spring shoes 13 disposed about the lower end of the housing 10 and a similar plurality or series of spring shoes 14 disposed about the upper end of the housing 10, such spring shoes extending into contact with the walls of the bore and holding the instrument substantially centered within the bore.

A suitable compass 15 is secured within the housing 10 and is illustrated herein as a gyroscopic compass, though it will be understood by those skilled in the art that any other character or type of compass may be employed so long as it has the characteristic of holding an indicating element directed toward the true north or toward any other selected point of the compass, or if desired, a simple gyroscope may be used which will have some portion or indicating element thereon movable at a known rate of speed and from which a calculation of the compass direction at any given instant may be made.

In the form of the device illustrated herein, the gyroscopic compass 15 has one of its gimbals 16 supported for rotation upon a mounting plate 17 extending across and rigidly secured near the lower end of the housing 10, while the opposite bearing for the gimbal 16 comprises a suitable bearing member 18 carried by a mounting 19 disposed immediately above the gyroscopic compass 15. We employ in our instrument an analyzing means for determining the compass direction for the deviation of the well bore, one part of which comprises a compass point orientation analyzing device 19a, the device 19a including a gimbal shaft 19b mounted for rotation on the bearing member 18 so that an arm or wiper 20 rigidly connected thereto may be held in fixed angular relationship relative to a meridian passing through the instrument while the instrument rotates thereabout. The wiper 20 carries an arm or pointing member which projects downwardly to engage a wiping contact or ball 21 arranged to

move about a contact plate 22 in a circular path.

By referring particularly to Fig. 3, it will be observed that the contact plate 22 is constructed with a metal disk-like portion 23 preferably with a ring 24 of insulating material surrounding the periphery of the same, and acting as a spacer in spacing a resistance ring 25 away from the periphery of the disk 23. The ring 25 is preferably formed of some suitable high resistance material such as a carbon ring and the insulation ring 24 is preferably undercut slightly below the upper surfaces of the disk 23 and the ring 25 to provide a depression 26 constituting the trackway about which the ball contact 21 may travel. The effect of the gyroscopic compass 16 will be to maintain the wiper arm 21 and its ball contact directed in a predetermined compass direction; for example, true north, irrespective of the rotation of the casing 10 during its passage upwardly and downwardly in the well bore.

Disposed immediately above the compass point orientation analyzing device 21 is a bore hole orientation analyzing device 27 which includes a contact plate 27a constructed similarly to plate 22 in that it includes a central portion or disk of metal 28 and an outer ring of high resistance material 29 spaced from and insulated from the disk by means of an insulation ring 30. The upper surface of the metal disk 28 is preferably rounded or cone-shaped so that a ball contact 31 disposed thereon will constantly be urged outwardly toward the resistance ring 29. The resistance ring preferably is somewhat above the upper surface of the plate 28 so that the ball will always contact both the metallic plate 28 and the resistance ring 29, and by reason of the conical shape of the surface of the plate 28 the ball will always assume a position representing the low side of the casing 10 as it is disposed within the well bore. This low point of the casing 10 is, of course, diametrically opposed to the direction taken by the well bore as it deviates from the true vertical.

Our analyzing means also includes a device for comparing the position of the gyroscope contact 21 (maintained at a fixed angle to a meridian by the gyroscope 15) with the position of the contact 31 which represents the direction of the deviation of the well bore so that the direction of the well bore may be referred to the meridian. This means may include a pair of contact arms or rotary members 32 and 33 associated respectively with the resistance rings 25 and 29. These contact arms are arranged to engage their respective resistance rings and be rotated therearound while being maintained in a fixed angular relationship relative to each other by means of a vertically extending shaft member 34 to which each of the arms 32 and 33 may be secured.

In order that the proper electrical connections may be established, we prefer to interpose insulating material 35 between each of the arms 32 and 33 and the shaft 34 to which they are secured. The shaft 34 may be secured against downward axial movement by means of a collar 36 secured to the shaft 34 in a position to engage a transversely extending plate member 37 secured to the side walls of the casing 10.

In order that the contact arms 32 and 33 may be rotated about the periphery of the resistance rings 25 and 29 in order to compare the relative positions of the ball contacts 21 and 31, we provide a synchronous motor 38 which may be secured within the housing 10 in any suitable man-

ner and arranged to rotate the shaft 34 through suitable reduction gearing 39. The motor 38 is also arranged to simultaneously rotate another vertically extending shaft 40 disposed above the motor 38 and journaled for rotation in suitable bearing members 41 and 42 carried in transversely extending plate members 43 and 44 secured to the side walls of the casing 10. The shaft 40 is drivably connected to the shaft of the motor 38 by means of reduction gearing 45. For reasons to be explained hereinafter the reduction gearing 39 and 45 are so arranged that the contact arms 32 and 33 will make two complete revolutions while the shaft 40 is making one complete revolution.

15 The shaft 40 carries a contact arm 46 which is rotatable therewith, being suitably secured to the shaft 40 and insulated therefrom by means of suitable insulating material 47. The contact arm 46 is arranged to contact a commutating and transfer device 47a carried in an insulating sleeve 48 secured to the side walls of the container 10.

20 As illustrated particularly in Fig. 3, the transfer mechanism 47a is preferably constructed in a ring shape and provided with alternate contact segments 49 separated from each other by insulating segments 50. The insulating segments are 25 preferably made slightly wider than the width of the contacting end of the rotary contact member 46 so that this member will contact only one of the plurality of contact segments 49 at any one time. A plurality of these segments, together with their interposed insulating segments 50 are 30 distributed over approximately one-half of the full circle provided by the commutating member 47a, the remaining half of the circle comprising a semi-circular slip ring 51 of electrically conducting material.

35 Secured within the casing 10 and disposed immediately above the plate member 43, we provide a pair of resistance units 52 and 53 and a pair of rectifying units 54 and 55. These units may be of conventional construction and suitably secured within casings adapted in turn to fit within the casing 10 and be secured thereto.

40 Directly above the rectifier unit 55 we provide a plurality of inclined plane and rolling ball type of angle measuring units 56. These units may be constructed as disclosed and described in a co-pending application filed by Emmett M. Irwin, et al., Serial No. 162,792, on September 7, 1937, and each may include a body member 57 which is provided with a conically depressed upper surface 58 upon which is rested a spherical metal ball 59. A suitable contact ring 60 may be supported in an insulating sleeve 61 in a position above the conical surface 58 such that when the ball 59 is rolled from the central depression in which it is rested to the outer edge of the supporting member 57, an electrical circuit will 55 be established between the contact ring 60 and the supporting member 57.

50 The included angle between the sides of the conical surface 58 is made different for each of the plurality of angle measuring units 56 provided, being preferably arranged in regular angular steps of 1° , the uppermost surface having an included angle of 179° . It will be readily apparent to those skilled in the art that should the casing 10 be disposed from the vertical at an angle in excess of one-half of 1° the upper ball member will roll out of the central depression within which it is rested and establish an electrical circuit between its contact ring and the 55 supporting member upon which it rolls. If these

cone-shaped supporting surfaces are arranged in such manner that the included angle of the cone of one of the members is 1° smaller than the next member above, the number of balls which will roll out of the central depression into contact with their associated contact rings, will represent the number of half degrees that the instrument is inclined from the vertical.

The instrument is capped by means of a cap member 62 which may be secured to the casing 10 by means of a threaded adapter unit 63 threadedly engaged with the casing 10 and providing also a threaded engagement for the cap 62. The cap 62 is provided with a packing and clamping member 64, for securing and sealing the supporting and electrical conductor cable 7. In order that proper connection may be established between a central electrical conductor 65 forming a part of the cable 7 and the equipment previously described, we provide a connection block 66 which is secured to the cap member 62 and provided with a terminal contact 67 to which the electrical conductor 65 may be attached.

The connection block 66 is provided with a spring contact member 68 connected electrically to the terminal contact 67 and arranged to engage a complementary contact member 69 carried by and insulated from the adapter member 63. The contact member 69 is provided at its lower end, which is disposed within the interior of the casing 10, with a contact terminal 70 from which all of the power for operating the previously described electrical mechanisms carried by the casing 10 is derived.

The equipment which is maintained at the ground surface and carried in the service truck 8 includes an alternating current generator 71 which is arranged to be driven from any suitable source of power such as the engine of the truck 8, a disconnect switch 72 connected in the main circuit of the generator 71 for disconnecting the equipment from the generator, a starting switch 73 which may be operated in a manner to be described hereinafter to place the equipment in operation, and a receiving and translating means illustrated herein as a dual recording ammeter 74. The ammeter 74 may be of a common type such as is illustrated in Fig. 5 and include a synchronous electric motor 75 which is connected by suitable belting or gearing (not shown) for feeding a chart 76 through the instrument at a substantially constant rate of speed.

The recording ammeter 74 includes a pair of load responsive elements or ammeters 77 and 78 which are each arranged to move associated needles 79 and 80 over scales 81 and 82. The needles 79 and 80 are provided with pens 83 and 84 or other suitable marking devices for scribbling a line on the chart 76 as the chart 76 is moved past these instruments.

As illustrated particularly in Fig. 4, rectifiers 85 and 86 are respectively associated with the ammeters 77 and 78 and are connected in series therewith. The rectifiers 85 and 86 are of the half wave type and so connected that each of the ammeters 77 and 78 respond only to one-half of each of the cycles of alternations present in the alternating current generated by the generator 71. In order that the ammeter 77 may respond to one-half of each of the cycles while the ammeter 78 may respond to the alternate half, we connect the rectifiers 85 and 86 in reverse relationship relative to each other.

The manner in which the equipment operates may best be understood by referring to Fig. 4

and assuming certain operating conditions and describing the manner in which each of the associated mechanisms operate and cooperate with the other associated mechanisms to transmit to the ground surface the angle of inclination of the well bore at the point where the reading is being taken, together with the compass direction which such deviation assumes. The equipment is placed in operation by starting the alternating current generator 71, one terminal of which may be connected to the outer sheath or grounded portion 87 of the cable 7 and the other terminal of which may be connected by means of a conductor 88 to the line switch 72. The starting switch 73 and the line switch 72 are then closed to transmit power over conductors 90a and 90b connected in parallel with each of the ammeters 77 and 78 to the electrical conductor portion 65 of the cable 7. The closing of the starting switch 73 prevents the momentary high inrush of current required to start the motors for the gyroscope 15 and the synchronous motor 38 from passing through the sensitive windings of the ammeters 77 and 78. If the ammeters 77 and 78 are so constructed as to be able to withstand this relatively high current, the switch 73 need not be employed. After these motors have been started the switch 73 is opened and left in the open position to allow the current to flow through the ammeters 77 and 78 which are connected by means of parallel circuits 89 and 90 between the electrical conductor portion 65 of the cable 7 and the load side of the line switch 72.

The circuit 89 includes the ammeter 77 and its associated rectifier 85 while circuit 90 includes the ammeter 78 and its associated rectifier 86. Power then flows down conductor 65 to the instrument 6 where the conductor 65 is connected to one terminal of the gyroscope motor 15, the other terminal of which is connected to the grounded circuit 87. Upon closing the switch 72 the gyroscope motor is caused to revolve and if the instrument is of the gyroscopic compass type the gimbal 16 and the shaft 18 secured thereto will assume a fixed angular position relative to the meridian passing through the location of the instrument. We prefer, for the sake of convenience, to secure the contact arm 20 to the shaft 18 in such position that the arm 20 will point to the true north.

If, on the other hand, the gyroscopic instrument 15 is of the simple gyroscope type, the contact arm 20 may be oriented relative to the true north before the instrument is lowered in the well bore. As soon as the gyroscope 15 is put into operation, the instrument is lowered into the well bore to the desired depth at which time readings of the angle of inclination and the direction of deviation may be determined from recordings made upon the chart 76 at that time.

Let us assume that at the point at which the measurement is being taken, the well bore is inclined 1° to the vertical and drifts northwest. If the bore is inclined at an angle of 1° to the vertical, two of the ball members 59 will lie in contact with their associated contact rings 60 and complete an electrical circuit between the two associated base members 57 and rings 60.

In order that this angle of inclination may be transmitted to the ground surface, we connect each of the supporting members 57 to the grounded casing 10 of the instrument, such connection being indicated on the wiring diagram

(Fig. 4) as by conductor 91. Each of the contact rings 60 is connected to a corresponding commutator segment 49 by means of conductors 92a, 92b, etc., as many conductors being provided as there are contact rings 60 and commutator segments 49.

The contact arm 46 which is associated with the commutating device 47a is electrically connected by means of a conductor 93 to one terminal of the rectifier 55. The connection between the conductor 93 and the contact arm 46 may be established by means of a brush member 94 secured to the insulating sleeve 48 in a position to wipe a cylindrical hub portion 95 of the contact arm 46. The other side of the rectifier 55 is connected by means of a conductor 96 to one terminal of the resistor 53, the other terminal of which is connected to the electrical conductor 65 forming a part of the cable 7.

It will be observed that if the contact arm 46 is rotated past its plurality of segments 49 in a counter-clockwise direction, as viewed in Fig. 4, an electrical circuit will be completed and interrupted between the conductors 87 and 65 through the rectifier 55 and the resistor 53 as many times as there are ball members 59 in contact with the contact rings 60 associated therewith. Rotation of the arm 46 in order to provide this commutating of the circuit 93 is imparted by means of the synchronous motor 38 whose terminals are connected directly across the supply conductors 87 and 65 so that this motor may be in operation continuously during the time the instrument is disposed in the well bore.

Since the rectifier 55 is of the half wave type, only one-half of the complete cycle of alternations in the current flowing in the conductors 87 and 65 will pass through the conductor 93 and the ball members 59 included in this circuit. The rectifier 55 is so placed in the circuit 93 that the current flowing therethrough will also flow through the rectifier 86 and the ammeter 78. During such time as the contact arm 46 is in contact with a segment 49 to which a circuit has been completed by one of the balls 59, a full metallic circuit will be completed from the generator 11 through the ammeter 78 which includes only the resistance unit 53 as a load. The magnitude of current flowing through the ammeter at this time is, therefore, determined by the resistance of the resistor 53.

We preferably choose this resistance of such value that the ammeter 78 will move its needle 79 through approximately half of its total allowable travel. In the assumed case then it will be seen that as the contact arm 46 is rotated past its contact segments 49 in response to the rotation of the motor 38, the circuit will be completed through the ammeter 78 twice corresponding to the two balls 59 which have been moved into contact with their contact rings 60 as a result of the instrument 6 being disposed at a 1° angle to the vertical. These two completions and interruptions of the circuit to the ammeter 78 will cause the recording made on the chart 76 to appear somewhat as indicated in Fig. 6 and include two peaks 97 and 98 in the line 99 which is drawn on the chart 76 by the ammeter 78. Since the operator making the survey knows that each one of these peaks 97 and 98 corresponds to an angle of inclination of the well bore of one-half of 1°, he is immediately informed that the well

bore deviates from the vertical at the point being surveyed by 1°.

As previously described, substantially one half of each full circle of revolution of the contact arm 46 is employed in transferring the conductor 93 sequentially to each of the segments 49, the remaining half circle of revolution establishing a connection between the conductor 93 and the slip ring portion 51. We prefer to use this remaining half of the revolution of the contact arm 46 for the determination of the azimuth of the line along which the well bore is deviating. We accordingly connect the slip ring 51 to the contact arm 33 as by means of a conductor 100 and the plate portion upon which the ball member 31 rests to the grounded outer case 10 of the instrument, such connection being indicated on Fig. 4 by conductor 101.

In a similar manner the plate member 23 of the unit associated with the gyroscope 15 is connected to the grounded case 10, such connection being indicated diagrammatically in Fig. 4 as conductor 102, while the movable arm 32 associated therewith is connected by means of a conductor 103 to the rectifier 54, the other side of said rectifier being connected by means of a conductor 104 to the resistor 52. The resistor 52 has its other terminal connected to the electrical conductor 65.

As previously mentioned, the gearing which is interposed between the shaft of the motor 38 and the shaft carrying contact arms 32 and 33 and the gearing interposed between the motor 38 and the shaft connecting the contact arm 46 is so arranged that the arms 32 and 33 are caused to make one complete revolution during the time the arm 46 is traversing a half of a revolution.

Referring first to the contact arm 32, it will be noted that the electrical circuit is completed from conductor 87 through conductor 102 to the base member 23 of the gyroscopically controlled unit, thence through the ball contact 21 to the resistance ring 25 where the circuit splits, one part travelling around the resistance ring in a clockwise direction, the other part travelling therearound in a counter-clockwise direction, these two parts meeting at the junction between the contact arm 32 and the resistance ring. The circuit then extends from the contact arm 32 via conductor 103 through the rectifier 54 and resistor 52 to the other line conductor 65.

We have arranged the rectifier 54 relative to conductors 103 and 104 in such manner that the half cycle of the alternating current which flows through this rectifier is the same half cycle which flows through the ammeter 78 so that the ammeter 78 will respond to changes in resistance in the previously described circuit.

It will be noted that the resistance of this circuit will vary from a maximum, at the point where the contact arm 32 is diametrically opposed to the position of the ball contact 21 or when the arm 32 is pointing due south, to a minimum when the arm 32 has rotated one half of a revolution from the previously described position to a position pointing due north at which time all of the resistance of the resistance ring 25 is cut out of the circuit.

The contact arm 32, resistance ring 25, and the ball contact 21 therefor comprise a variable load means operable to impose a load on the generator 11 which varies in correspondence with the determinations of the analyzing means,

Since this variable resistance is connected in series with the ammeter 77 and the alternating current generator 74, it follows that the indications of the recording ammeter 77 will vary from a minimum reading when the arm 32 is pointing due south; to a maximum reading when the arm is pointing due north so as to describe a curve such as the curve 105 indicated in Fig. 6.

The point of maximum deflection of the ammeter corresponding to the ammeter reading at the time the contact arm 32 is pointing due north establishes peaks such as that indicated at 106 in Fig. 6. Simultaneously with the rotation of the arm 32 to establish the peak 106 on the chart 76 to indicate the true north position, the arm 33 is caused to revolve about its associated resistance ring 29 to cause a recording upon the chart 76 indicating the lowermost position of the track upon which the ball contact 33 travels. Current for this measurement flows from the grounded conductor 87 through conductor 101 and ball contact 31 to the resistance strip 29 where the path divides, one path leading in a clockwise direction around the resistance ring 29, while the other path leads in a counter-clockwise direction therearound, these paths meeting at the junction between the contact arm 33 and the resistance strip 29. The current then flows from the arm 33 over conductor 100 to the slip ring 51, through the movable arm 46 in contact therewith and conductor 93 attached to said movable arm and thence through rectifier 55 and resistor 53 to the other side of the line 65.

As has been pointed out, current flowing through the rectifier 55 is measured by the ammeter 78 so that as the resistance in the previously described circuit varies from a maximum at the time the arm 33 is positioned diametrically opposite the location of the ball contact 31 to a minimum at the time when the arm 33 is positioned adjacent the ball contact 31, the ammeter indications will vary from a minimum to a maximum, the maximum reading occurring at the time the contact arm 33 is adjacent the ball contact 31. This ammeter will thus draw an extension of the curve 89, such as that indicated at 107 in Fig. 6, having a peak 108 corresponding to the point of maximum current and representing the time at which the movable contact 33 is angularly disposed relative to a predetermined reference point on the housing established by the beginning or end of the commutator segment 51, in exactly the same fashion as the ball contact 31 is angularly disposed relative to this reference point.

Since the synchronous motor 75 is employed to drive the chart 76 and the synchronous motor 38 is employed to drive the contact arms 32 and 33, it follows that a specified length of chart will always correspond to one complete revolution of the arms 32 and 33 independently of the speed at which the arms are rotated and the chart is fed. It will be further observed that this distance is the distance separating the two peaks 106 in the curve 105 and represents an angular displacement of the arms 32 and 33 of exactly 360°. This distance is indicated on Fig. 6 by the dimension line bearing the reference character 109.

It will be further observed that since we prefer, as previously mentioned, to rotate the contact arms 32 and 33 in a counter-clockwise direction, the arm 32 will, under the assumed conditions as illustrated in Fig. 4, first arrive at the

5 true north position corresponding to one of the peaks 106 and at a later time the arm 33 will arrive at a point adjacent the ball contact 31 corresponding to the low side of the track upon which it travels or a direction diametrically opposed to the direction of deviation of the well bore.

10 Since the position assumed by the ball contact 31 is diametrically opposite to the direction of deviation of the well bore, we prefer to locate the arm 33 in a position diametrically opposed from the position of the arm 32 so that after the arm 32 has assumed the true north position, the amount of angular displacement required to move the arm 33 into a position pointing in a direction diametrically opposite to the direction of deviation of the well bore will be exactly equal to the included angle between the deviation of the well bore and a meridian passed through the instrument.

15 20 In order to determine this angular deviation from the meridian, a distance 110 (see Fig. 6) separating the peak 106 corresponding to the true north from the peak 108 corresponding to the direction of deviation of the bore may be measured and compared to the previously mentioned distance 109.

25 30 If, as in the assumed example, the well is deviating northwest, the distance 110 will equal exactly one-eighth of the distance 109, and since the distance 109 represents 360°, the distance 110 will represent one-eighth of 360° or 45° from the north. Since the synchronous motor 38 is arranged to rotate the arms 32 and 33 in a counter-clockwise direction when viewed from above or from north through west to south, it follows, since the peaks 108 occur at a time later than the peak 106, the well bore must be deviating west of north by 45° or in the direction northwest.

35 40 Our device also provides means for determining the angular position of the instrument housing relative to a predetermined reference direction independently of determinations of the compass direction assumed by the well bore.

45 50 After the instrument has transmitted to the ground surface the angle of inclination of the well bore to the vertical, no current will flow through the ammeter 78 and the line 88 drawn thereby on the chart 76 will be a straight line indicating this zero current condition. As soon, however, as the wiper arm 46 arrives at the predetermined reference point on the housing and establishes an electrical connection with the slip ring segment 51, the line 88 drawn by the ammeter 78 will have a break in it such as that indicated at 111 in Fig. 6 at which time the ammeter 77 indicates the amount of current flowing through the resistance ring 29. The break or 55 60 point of discontinuity 111 in the line 88 indicates the instant at which the movable arm 46 came into contact with the predetermined reference point on the instrument housing. If then a dimension 112 is measured from the break 111 to the peak 106 of the curve 105 representing the relative location of the true north direction, the comparison between the dimension 112 and the dimension 109 will give the angular position of the reference point on the instrument housing relative to the true north-south line.

65 70 75 It will be noted, therefore, that with this arrangement a number of geometrical relationships may be ascertained from an inspection of the record furnished by the survey instrument of our invention; namely, the angular disposition of the

housing relative to a predetermined reference direction, the angular disposition of the housing relative to the direction taken by the deviation of the well bore from the vertical, the angular direction of the deviation of the well bore relative to a predetermined reference direction, and the angle of inclination of the well bore to the vertical.

It will be apparent to those skilled in the art that with all of this data, together with depth measurements which may be taken by measuring the amount of cable payed out from the cable reel in lowering the instrument in the well bore, the precise course of the well bore may be accurately mapped and other useful data tabulated.

It will be observed that with this arrangement, a single cable comprising an insulated electrical conductor and a grounded cable sheath may be employed with the previously described apparatus to determine, whenever desired at any point in a well bore, the angle which said bore deviates from the vertical and the angular position of such deviation referred to any selected horizontal reference line.

It is apparent that all sources of error, such as the resistance of the cable or changes in the resistance of the various elements employed due to temperature or pressure changes, are obviated through the use of this system which depends upon the synchronous timing between the speed of feed of the chart and the speed of rotation of the analyzing devices 22 and 27.

The indications do not depend upon the value of current indicated by the ammeter charts but upon the location of well defined peaks in these curves relative to each other. In the case of the vertical angle, the magnitude is determined purely by the number of peaks irrespective of their relative positions.

It is accordingly apparent that we have provided a survey instrument which may be lowered to any desired depth in a well bore upon a cable of the character described and which operates to transmit to the ground surface readily translatable indications of the angle of deviation of the well bore from the vertical and the direction which such deviation assumes relative to a horizontal reference direction line.

While we have shown and described the preferred embodiment of our invention, we do not desire to be limited to any of the details of construction shown or described herein, except as defined in the appended claims.

We claim:

1. In an oil well survey device, an instrument housing insertable in a well bore with its axis aligned with the axis of said bore, said housing containing the following instrumentalities; orientation means for determining the angular orientation of said housing with respect to the direction of inclination of said well bore, compass means for determining the angular orientation of said housing with respect to a predetermined compass direction, and transmitting means for simultaneously transmitting to the ground surface a pair of comparable signals, one for each of the determinations of said orientation means and said compass means; and translating means at the ground surface including means for receiving said signals, and means actuated by said signals for visibly indicating said signals in a comparable relation to each other whereby said signals may be visually compared to determine the direction of inclination of said well bore with respect to said predetermined compass direction.

2. In an oil well survey device, an instrument housing insertable in a well bore with its axis aligned with the axis of said bore, said housing containing the following instrumentalities; orientation means for determining the angular orientation of said housing with respect to the direction of inclination of said well bore, compass means for determining the angular orientation of said housing with respect to a predetermined compass direction, timing means defining a repeating time cycle, and transmitting means actuated by said timing means and coupled to said orientation means and said compass means for simultaneously transmitting to the ground surface a pair of signals of varying amplitude, the positions of the maximum amplitude of which in each of said time cycles are a measure of the determinations made by said orientation means and said compass means; and translating means at the ground surface including means for receiving said signals, and recording means for recording said signals with the maximum amplitude thereof in a linear spaced relation to each other corresponding to the positioning of said maximum amplitude in said time cycle, whereby the linear distance separating said maximum amplitudes of said recorded signals may be compared with the linear distance separating the maximum amplitudes of one recorded signal from the repetition thereof to determine the direction of inclination of said well bore with respect to said predetermined compass direction.

3. In an oil well survey device, an instrument housing insertable in a well bore with its axis aligned with the axis of said bore, said housing containing the following instrumentalities; means defining a reference point, orientation means having a gravity actuated member movable by inclination of said housing to a position indicating the angular relation of said reference point to the direction of inclination of said well bore and including one rotary member mounted for rotation independently of said gravity member, compass means having an indicating member capable of assuming a predetermined compass direction and including another rotary member mounted for rotation independently of said indicating member, means for synchronously rotating said rotary members to define one time cycle for each full circle rotation thereof, and transmitting means coupled to said rotary members for transmitting three signals to the ground surface during one time cycle, one signal when said one rotary member is moved to angular coincidence with said gravity member, another signal when said other rotary member is moved to angular coincidence with said indicating member, and a third signal when said rotary members are moved to angular coincidence with said reference point; and translating means at the ground surface including means for receiving said signals, and recording means for recording said signals in the same linear spaced relation to each other as said signals are spaced in said time cycle.

4. In an oil well survey device, an instrument housing insertable in a well bore with its axis aligned with the axis of said bore, said housing containing the following instrumentalities; means defining a reference point, orientation means for determining the angular orientation of said reference point with respect to the direction of inclination of said well bore, compass means for determining the angular orientation of said reference point with respect to a predetermined

compass direction, timing means defining a repeating time cycle, and transmitting means actuated by said timing means and coupled to said orientation means and said compass means for simultaneously transmitting to the ground surface a pair of signals of varying amplitude, the positions of the maximum amplitude of which in each of said time cycles are a measure of the determination made by said orientation means and said compass means; and translating means at the ground surface including means for receiving said signals, a record chart, indicating means actuated by said signals to make marks on said chart representative of the varying amplitude of said signals, and means for moving said chart past said indicating means in synchronism with the operation of said timing means, whereby the relative linear positions of the maximum signal amplitudes represented by said marks on said chart are identical with the positioning of said maximum amplitude in said time cycle.

5. In an oil well survey device, an instrument housing insertable in a well bore with its axis aligned with the axis of said bore, said housing containing the following instrumentalities; means defining a reference point, orientation means having a gravity actuated member movable by inclination of said housing to a position indicating the angular relation of said reference point to the direction of inclination of said well bore and including one rotary member mounted for rotation independently of said gravity member, compass means having an indicating member capable of assuming a predetermined compass direction and including another rotary member mounted for rotation independently of said indicating member, means for synchronously rotating said rotary members to define one time cycle for each full circle rotation thereof, and transmitting means coupled to said rotary members for transmitting three signals to the ground surface during one time cycle, one signal when said one rotary member is moved to angular coincidence with said gravity member, another signal when said other rotary member is moved to angular coincidence with said indicating member, and a third signal when said rotary members are moved to angular coincidence with said reference point; and translating means at the ground surface including means for receiving said signals, a record chart, indicating means actuated by said signals to make marks on said chart, and means for moving said chart past said indicating means in synchronism with the rotation of said rotary members, whereby the relative linear positions of said marks on said chart are identical with the relative angular positions of said gravity actuated member, indicating member and reference point.

6. In an oil well survey device, an instrument housing insertable in a well bore with its axis aligned with the axis of said bore, said housing containing the following instrumentalities; means defining a reference point, orientation means for determining the angular orientation of said reference point with respect to the direction of inclination of said well bore, compass means for determining the angular orientation of said reference point with respect to a predetermined compass direction, timing means defining a repeating time cycle, and transmitting means actuated by said timing means and coupled to said orientation means and said compass means for repeatedly transmitting to the ground surface a

7. In an oil well survey device, an instrument housing insertable in a well bore with its axis aligned with the axis of said bore, said housing containing the following instrumentalities; inclination responsive means for determining the angle of inclination of said well bore, means defining a reference point, orientation means for determining the angular orientation of said reference point with respect to the direction of inclination of said well bore, compass means for determining the angular orientation of said reference point with respect to a predetermined compass direction, timing means defining a repeating time cycle, and translating means at the ground surface including means for receiving said signals, a record chart, indicating means actuated by said signals to make marks on said chart, and means for moving said chart past said indicating means in synchronism with the operation of said timing means, whereby the relative linear positions of said marks on said chart are identical with the positioning of said signals in said time cycle.

15. In an oil well survey device, an instrument housing insertable in a well bore with its axis aligned with the axis of said bore, said housing containing the following instrumentalities; inclination responsive means for determining the angle of inclination of said well bore, means defining a reference point, orientation means for determining the angular orientation of said reference point with respect to the direction of inclination of said well bore, compass means for determining the angular orientation of said reference point with respect to a predetermined compass direction, timing means defining a repeating time cycle, and a transmitting means actuated by said timing means and coupled to said inclination responsive means, orientation means and compass means to simultaneously transmit to the ground surface during one time cycle a pair of comparable signals corresponding to the determinations of said orientation means and said compass means and to transmit during a subsequent time cycle a plurality of other signals, the number of which is representative of the determination of said inclination responsive means; and translating means at the ground surface including means for receiving said signals, and recording means actuated by said signals for visibly indicating said comparable signals in a comparable relation to each other and recording the number of said other signals, whereby visual comparison of said signals indicates the angle of inclination of said well bore and the compass direction of said inclination.

20. In an oil well survey device, the combination of: a survey instrument insertable in a well bore with its axis aligned with the axis of said bore including orientation means for determining the angular orientation of the deviation of said well bore relative to the angular position of said instrument, and compass means for determining the angular orientation of said instrument position relative to a predetermined reference direction; a source of alternating current at the ground surface; electric motor driven timing means carried by said instrument cooperating with said orientation means and said compass means for repeatedly transmitting to said ground surface a pair of signals both embraced within one time cycle, one signal representative of the determination of said orientation means and another signal representative of the determination of said compass means and for establishing a time lapse between said one signal and said other signal relative to the time cycle of said repetition such that the ratio of said time lapse to said time cycle is equal to the ratio between said angular orientations; means connecting said timing means to said source of alternating current; and receiving means at said ground surface connected to said source of alternating current to operate in synchronism with said timing means

for receiving and visibly indicating said signals in a comparable relation to each other whereby visual comparision of said signals indicates the relation between said time lapse and said time cycle to thereby provide an indication of the angular relation between the deviation of said well bore and said predetermined reference direction.

9. In an oil well survey instrument including a housing insertable in a well bore and having an axis alignable with the axis of said bore and means defining a reference point on said housing, a device for measuring the angular disposition of said reference point relative to the direction of deviation of said well bore from the vertical, comprising: an electrically conductive supporting plate in said housing disposed perpendicularly relative to the axis thereof; an electrically conductive resistance element encircling said plate and insulated therefrom for defining a circular trackway; an electrically conductive rolling member carried on said plate and movable by gravity around said trackway to the low side thereof to define a housing low point by electrically connecting the low side of said resistance strip to said plate when the axis of said housing is disposed at an angle to the vertical; a rotary member engaging said resistance strip to form an electric circuit between said rotary member and said plate through said resistance strip and said rolling member; means mounting said rotary member for movement about said resistance strip from a position corresponding to said reference point to said low point to traverse an angle corresponding to the angle between said points and to thereby vary the resistance of said

electric circuit; and means in said circuit responsive to variations in the resistance thereof for indicating the magnitude of the angle traversed by said rotary member.

5 10 15 20 25 30 35

10. In an oil well survey instrument including a housing insertable in a well bore and means defining a reference point on said housing, a compass device for determining the compass direction of said reference point, comprising: an electrically conductive resistance ring carried by said housing and insulated therefrom; a pointing member of electrically conductive material engaging said ring, a compass means in said housing for moving said pointing member about said resistance ring to a position defining a predetermined compass direction; a rotary member of electrically conductive material engaging said resistance ring to form an electric circuit between said rotary member and said pointing member through said resistance ring, means mounting said rotary member for movement about said resistance ring from a position corresponding to the location of said reference point to a position corresponding to the position of said pointing member to traverse an angle corresponding to the angle between said reference point and said predetermined compass direction and to thereby vary the resistance of said electric circuit; and means in said circuit responsive to variations in the resistance thereof for indicating the magnitude of the angle traversed by said rotary member.
